UNITED STATES PATENT OFFICE.

JOHN BEAN, OF LOS GATOS, CALIFORNIA.

SPRAY-NOZZLE.

SPECIFICATION forming part of Letters Patent No. 417,464, dated December 17, 1889.

Application filed July 31, 1889. Serial No. 319,330. (No model.)

To all whom it may concern:

Be it known that I, JOHN BEAN, of Los Gatos, Santa Clara county, State of California, have invented an Improvement in Spray-Nozzles; 5 and I hereby declare the following to be a full, clear, and exact description of the same.

My invention relates to the class of nozzles or tips specially adapted for spraying and used in the treatment of infected trees, shrubs, 10 vines, &c.; and my invention consists, essentially, in a novel imperforate packing plate or sheet controlling the nozzle-passage and exit-port.

It consists, also, in the novel constructions, 15 arrangements, and combinations hereinafter fully described, and specifically pointed out in the claims.

The object of my invention is to provide a spray-nozzle capable of effective operation 20 under a smaller pressure than usual, and one which will not be affected injuriously in its adjustable or working parts by the liquid passing through it.

Referring to the accompanying drawings 25 for a more complete explanation of my invention, Figure 1 is a perspective view of my spray-nozzle. Fig. 2 is a longitudinal section of the same. Fig. 3 is a perspective view of the plate or sheet C. Fig. 4 is a perspective 30 view of the clamp-plate D and regulating-lug E. Fig. 5 is a view of the nozzle or tip with the parts C and D removed. Fig. 6 is a section of a modified or double nozzle or tip. Fig. 7 is a front edge view of the same.

35 A is the nozzle or tip, having at its rear end the internally-threaded socket a, by which it is screwed upon the hose-pipe. The passage a' of the nozzle or tip extends straight through it and terminates in a slight groove which 40 forms the exit-port b. This groove is made in the end of a wide bearing-surface B, formed on the front of the nozzle or tip, said surface being here shown as inclined to the plane of the passage a', whereby it partially intersects 45 and exposes said passage just back of the exit-port. It is not essential that this bearing-surface shall be so inclined, for it is only necessary that the passage shall lie exposed in it for a short distance back from its exit 50 end, and therefore the relative arrangement

of passage and surface may be in any manner giving this result.

Upon the bearing-surface B is laid a plate or sheet C, made of suitable packing material which will form a tight joint, and for the best 55 results this material should be flexible, such as rubber, as this will not be injuriously affected by the liquid used. This plate or sheet C has about the same superficial surface as the bearing-surface on which it rests, its forward edge being about flush with or just a little short of the front edge of the bearing-surface. This plate or sheet has no hole in it at all, but is entire, and, lying on the bearing-surface B, it covers and completes at its 60 middle front portion the exposed end of passage a' and lies just above the groove or port b.

E is a clamp-plate placed on the imperforate plate or sheet C and secured by screws d, 70 which pass down through the plate or sheet C and are seated in the bearing-surface B, so that said plate or sheet C is firmly clamped and bound between the plate D and the surface B, thereby serving in addition to its primary function of a sprayer, as will be presently explained, the secondary function of a packing-washer, making a tight joint. The forward edge of the clamp-plate D comes out 75 flush with the forward edge of the bearing-surface B, and said plate is made forked to receive the regulating lug E, which is pivoted to the plate at e and has an upwardly-extending arm e' at its back.

Rising from the nozzle or tip A is a piece 85 a², in which is seated the adjusting-screw F, the forward end of which bears against the arm e' of the regulating-lug E. The lug E rests upon the imperforate plate or sheet C, and its forward end on its underside is made 90 with a slight groove or concave e² in a plane just above the groove or port b in the surface B below.

The operation of the device is as follows: In the broadest view of its action the clamp- 95 plate D is to be regarded as a continuous surface, as if the lug E formed a rigid part of it. Now, this plate being screwed down upon the imperforate plate or sheet C causes the latter to serve as a packing, and also pressing and 100

biting down upon said plate or sheet holds the center of its front edge down directly over the exposed forward end of passage a' and over the port b , and partially conforming thereto by reason of its flexibility, sufficiently 5 obstructs said passage and port to convert the liquid into spray as it issues from the port. To improve this result, the slight groove or concave e^2 lends itself by allowing the upward curve of the edge of the flexible plate or sheet, and thus giving a nucleus to the issuing spray and concentrating it. Now, to understand how the spray is regulated in degree, the clamp-plate D and lug E are to be 10 regarded as separate pieces, the former holding the flexible plate or sheet C and the latter variably affecting its middle portion. For a fine spray, the screw F is set up and its end bearing on the arm e' of lug E turns said lug down, so that it pinches the flexible plate or 15 sheet down more closely into the exposed end of passage a' and port b , and for a coarser spray the screw is run back to relieve the lug, which thereupon relieves the plate or sheet. 20

In Figs. 6 and 7 I have shown a double construction. In this I have a bearing-surface B on each side of the nozzle or tip, said surfaces converging forwardly to a very thin edge. These surfaces the passage a' intersects, as before. An imperforate plate or 25 sheet C is laid on each surface, one of said plates or sheets being clamped by a plate (here lettered d') similar to plate D , with the exception that it is a continuous one having no regulating-lug E in it, but having a small groove or concave d' in the center of its forward edge, similar to the groove or concave e^2 in the lug E . It will be seen that in this 30 double construction the imperforate plates or sheets act similarly on both sides, while the lug E on one side is sufficient to regulate both, though it is obvious that a second lug, such as E , might be used.

In the use of spraying-nozzles in which a 45 rotary or movable valve or plug is employed, a serious difficulty is encountered arising from the fact that some of the liquids used corrode the metal of the nozzle, resulting in interference with the operation of the movable parts; but in my nozzle the imperforate plates or sheets, being made of rubber, are not injuriously affected, and they protect, in 50 their capacity as packing, the movable lug E from contact with the liquid; consequently there is no danger of the nozzle ever getting 55 out of working order. Nor is there anything to be feared from clogging in the use of my nozzle, as there is in the use of those devices in which perforated flexible diaphragms or 60 washers are used, for in my device any tendency to clog may be instantly relieved by relieving the movable lug E from the pressure of the screw F , or by relieving the clamping-plate. 65

I have found by experience that less pressure is required in the use of my nozzle to convert the liquid into spray.

Having thus described my invention, what I claim as new, and desire to secure by Letters Patent, is—

1. The nozzle or tip having a bearing-surface in which its passage lies exposed, said passage terminating in a groove which forms the exit-port, in combination with an imperforate packing plate or sheet lying on said bearing-surface and completing the exposed portion of the passage, and an independent plate for clamping the packing plate or sheet down onto the bearing-surface, substantially as described. 70

2. The nozzle or tip having a bearing-surface in which its passage lies exposed and terminates in a groove which forms the exit-port, in combination with an imperforate packing plate or sheet of flexible material lying on said bearing-surface and completing the exposed portion of the passage, and an independent plate for clamping the flexible packing plate or sheet down onto the bearing-surface, substantially as described. 75

3. The nozzle or tip having a passage through it and a bearing-surface at its front inclined to the plane of and partially intersecting said passage, in combination with an imperforate packing plate or sheet resting on said bearing-surface and forming a top for the passage, and a clamp-plate secured to the inclined bearing-surface and screwed down upon the flexible plate or sheet to hold it in place, substantially as described. 80

4. The nozzle or tip having a passage through it terminating in a groove forming an exit-port at its forward end, and having a bearing-surface on its front, in which said passage lies exposed back from its exit, in combination with an imperforate packing plate or sheet resting on said surface and completing the exposed portion of the passage, and a clamp-plate screwed to the bearing-surface and holding the packing plate or sheet in place, substantially as described. 85

5. The nozzle or tip having a passage through it terminating in a groove forming an exit-port at its forward end, and having a bearing-surface on its front, in which the passage lies exposed back from its exit-port, in combination with an imperforate flexible packing plate or sheet resting on said surface and completing the exposed portion of the passage, and a clamp-plate screwed down on the flexible packing plate or sheet, and having a groove or concave under its front and in line above the passage and exit-port, substantially as described. 90

6. The nozzle or tip having a passage through it terminating in a groove forming an exit-port, and having a bearing-surface at its front, in which the passage lies exposed back from its exit-port, in combination with the imperforate flexible packing plate or sheet resting on said surface and completing the exposed portion of the passage, a clamp-plate screwed down upon the flexible packing plate or sheet, and the regulating-lug pivoted to 95

and adjustable in the clamp-plate and bearing on the flexible packing plate or sheet, substantially as described.

7. The nozzle or tip having a passage 5 through it terminating in a groove forming an exit-port, and having a bearing-surface at its front, in which the passage lies exposed back from its exit-port, in combination with the imperforate flexible packing plate or sheet 10 on said surface and completing the exposed portion of the passage, a clamp-plate screwed down upon the flexible packing plate or sheet, and the regulating-lug pivoted to and adjustable in the clamp-plate and having a 15 groove or concave under its forward end in line above the exit-port, substantially as described.

8. The nozzle or tip having a passage 20 through it and a bearing-surface at its front, in which the passage lies exposed back from its exit end, in combination with the imperforate flexible packing plate or sheet resting on said surface and completing the exposed portion of the passage, the clamp-plate 25 screwed down upon said flexible packing plate or sheet, the regulating-lug pivoted in the clamp-plate and having an arm, and the adjusting-screw carried by the nozzle or tip and bearing on the arm for setting the lug on the flexible packing plate or sheet, substantially as described.

9. The nozzle or tip having a passage 30 through it terminating in a groove forming an exit-port and a bearing-surface at its front, in which the passage lies exposed back from its exit-port, in combination with the imperforate flexible packing plate or sheet resting on said surface and completing the exposed portion of the passage, the clamp- 35 plate screwed down upon the flexible packing plate or sheet, the regulating-lug pivoted in the clamp-plate and having a groove in its under side over the exit-port, the arm of the lug, and the adjusting-screw carried by the 40 nozzle or tip, substantially as described.

10. The nozzle or tip having a passage 45 through it and a bearing-surface at its front above and below, said surfaces converging forwardly and intersecting the passage, in combination with an imperforate packing 50 plate or sheet resting on each bearing-surface and forming walls for the exposed portion of the passage, and a clamp-plate screwed against each packing plate or sheet to hold it to place, substantially as described. 55

11. The nozzle or tip having a passage 60 through it and a bearing-surface at its front above and below, said surfaces converging forwardly and intersecting the passage, in combination with an imperforate flexible packing 65 plate or sheet resting on each bearing-surface and forming walls for the exposed portion of the passage, and a clamp-plate screwed against each packing plate or sheet and having corresponding grooves under their forward edges in line with the passage, substantially as described.

12. The nozzle or tip having a passage 70 through it and a bearing-surface at its front above and below, said surfaces converging forwardly and intersecting the passage, in combination with an imperforate flexible packing plate or sheet resting on each bearing-surface and forming walls for the exposed portion of the passage, a clamp-plate screwed 75 down on one flexible packing plate or sheet and having a groove in its under side in line with the passage, a clamp-plate screwed down on the other flexible packing plate or sheet, the regulating-lug pivoted in said last-named 80 clamp-plate and having a groove in its under surface, in line with the passage, the arm of the lug, and the adjusting-screw carried by the nozzle or tip, substantially as described.

In witness whereof I have hereunto set my 85 hand.

JOHN BEAN.
